UNITED STATES PATENT OFFICE.

ROBERT A. DUNNING, OF YARMOUTH, MAINE.

FABRIC.

No. 878,944.

Specification of Letters Patent.

Patented Feb. 11, 1908.

Application filed November 16, 1905. Serial No. 287,701.

To all whom it may concern:

Be it known that I, ROBERT A. DUNNING, a citizen of the United States, residing at Yarmouth, in the county of Cumberland and State of Maine, have invented a new and useful Fabric, of which the following is a specification.

This invention relates generally to fabrics, and particularly to a novel form of fabric in which the filler is composed of a highly absorbent and expansible material, preferably of comminuted sponge.

The object of the invention is to utilize waste or scrap sponge in the production of a fabric for various uses such as for bath towels, bath mats, wash cloths, harness pads and for other purposes too numerous to mention, the particles or pieces of sponge being combined in such manner as to present a thoroughly efficient and durable fabric for the purposes designed.

With the above and other objects in view, as will appear as the nature of the invention is better understood, the same consists in the novel form of fabric hereinafter fully described and claimed.

In the accompanying drawings forming a part of this specification, and in which like characters of reference indicate corresponding parts:—Figure 1 is a view in plan of a piece of fabric constructed in accordance with the present invention. Fig. 2 is a detail view of a length of the fabric for weaving purposes. Fig. 3 is a view in plan showing another manner in which the invention is carried into effect. Fig. 4 is a detail view of another form of the invention.

In carrying the procedure into effect, culled or scrap sponge, which is generally a waste product, is taken, and is sorted and freed from shells or other foreign matter or impurities, and is then run through a picking machine and is picked to any required degree of fineness. This product is then dusted, washed and dried. It is then treated with a suitable sizing, which may be either a gelatin size or a paraffin compound, and is spread out in thin sheets of proper thickness for intended use and is pressed, thereby causing the pieces of sponge to adhere to each

other. After the size has dried and set, the sheet of sponge is run through a quilting machine and sewed on lines 1 and 2. It is then cut between the lines of stitches to form threads 3, the size of which will be determined by the distance that the lines of stitches are spaced, and the thread thus presented is ready for weaving. For some purposes, it is only necessary to run the treated sheet of sponge through a quilting machine both ways as shown in Fig. 1, but where it is to be woven as shown in Fig. 3, the threads 3 are freed from sizing and are then woven on any suitable loom with any preferred material for the warp 4 and woof 5, the sponge forming the filling.

Under some conditions, instead of assembling the pieces of sponge by stitching, as described, they may be strung upon a thread 6 as shown in Fig. 4, and afterwards woven on a suitable loom in the manner described. In making the fabric, any quantity of sponge may be used so as to make a thick or thin fabric, the amount employed being controlled by the use to which the finished article is to be put.

The product of the procedure herein defined will be cheap, durable, and will for bathing purposes possess qualities that will render its use preferable to ordinary towels, such as Turkish, commonly in use.

As seen in Fig. 3, the warp and woof show through different places on the fabric and this is due to the fact that the sponge is dry, but when wet it will swell and make an even surface that will entirely conceal all of the body of the fabric. Of course, by including more sponge or by closely and tightly weaving it, the warp and woof may at all times be concealed from view.

It will be noted that the sponge used in this fabric maintains its moisture absorbing and retaining characteristics inasmuch as the cells of the sponge are not destroyed in the production of the fabric, each particle of sponge being of the same cellular nature as a complete large sponge.

Having thus described the invention, what is claimed is:

1. A fabric consisting of interwoven 100

threads and having particles of cut sponge upon certain of the threads.

2. A fabric comprising interwoven threads and particles of cut sponge supported thereby.
- 5 3. A woven fabric made up of threads having particles of cut sponge supported by the threads.

In testimony that I claim the foregoing as my own, I have hereto affixed my signature in the presence of two witnesses.

ROBERT A. DUNNING.
